JOURNAL BOX CONSTRUCTION FOR RAILWAY CARS

Theodore J. Sweger, Riverdale, Ill., assignor to Illinois Railway Equipment Company, Chicago, Ill., a corporation of Illinois

Filed June 7, 1961, Ser. No. 115,580
22 Claims. (Cl. 308—40)

This invention relates, generally, to railway car journal boxes and it has particular relation to axle journal guides therefor.

Among the objects of this invention are: To provide new and improved means for mounting journal guides in a journal box for a railway car; to employ for this purpose a one piece spring wire frame which permits application and removal of the journal guides for initial installation and for replacement and repair purposes; to arrange for the spring wire frame to react against the walls of the journal box and hold the journal guides against movement in vertical planes and to bias them against the side walls of the journal box; to interconnect the spring wire frame and the journal guides by wrapping the former around grooved intermediate portions of the latter; to locate each journal guide on a waste retainer rib and under the lower end of a brass stop column to limit its down and up movement respectively; to arrange for the end portions of the spring wire frame to overlie the side walls of the journal box with the ends outturned and extending into apertures in the side walls; to cause the end portions of the spring wire frame to bear against a vertical wall of the dust guard well at the inner end of the journal box; and to locate the portion of the spring wire frame interconnecting the journal guides in overlying relation to the concave bottom wall of the journal box for reacting against the same.

Other objects of this invention will, in part, be obvious and in part appear hereinafter.

In the drawings:

FIG. 1 is a view, partly in end elevation and partly in vertical section, showing a journal box and axle journal construction provided with journal guides supported in accordance with one embodiment of this invention.

FIG. 2 is a vertical sectional view, taken generally along the line 2—2 of FIG. 1, the axle being shown by a broken line outline in order to depict more clearly the details of construction of the support for the journal guides.

FIG. 3 is a horizontal sectional view, taken generally along the line 3—3 of FIG. 2.

FIG. 4 is a sectional view, taken generally along the line 4—4 of FIG. 2, and showing a slightly modified construction.

FIG. 5 is a view, similar to FIG. 1, and illustrating another embodiment of the invention.

FIG. 6 is a vertical sectional view taken generally along the line 6—6 of FIG. 5.

FIG. 7 is a horizontal sectional view taken generally along the line 7—7 of FIG. 6.

FIG. 8 is a view, similar to FIG. 1, and showing still another embodiment of the invention.

FIG. 9 is a vertical sectional view taken generally along the line 9—9 of FIG. 8.

FIG. 10 is a horizontal sectional view taken generally along the line 10—10 of FIG. 9.

FIG. 11 is a sectional view, taken generally along the line 11—11 of FIG. 9, and showing a modification of the construction.

FIG. 12 is a view, similar to FIG. 1, and showing a further embodiment of the invention.

FIG. 13 is a vertical sectional view taken generally along the line 13—13 of FIG. 12.

2

FIG. 14 is a horizontal sectional view taken generally along the line 14—14 of FIG. 13.

Referring now particularly to FIGS. 1, 2 and 3 of the drawings, it will be observed that the reference character 10 designates, generally, a railway car axle which, in FIGS. 2 and 3, is shown by a broken line outline in order to illustrate more clearly the details of construction of the invention. The railway car axle 10 includes an axle journal 11 provided with an end collar 12 and it is arranged to rotate about an axis of rotation or its longitudinal axis indicated at 13 in FIG. 1. The axle journal 11 is mounted within a railway car journal box, indicated generally at 14, which is of conventional construction. The railway car journal box 14 includes a horizontal top wall 15 from which vertical side walls 16—16 depend and they are interconnected at their lower ends by a bottom wall 17 which has a concave inner surface 18. This may be a cylindrical surface. The concave inner surface 18 of the bottom wall 17 terminates at its forward end in a concave inner surface 19 on the inner side of an end wall 20 which is located below a lid opening 21 (the lid not being shown). The rear end of the concave inner surface 18 of the bottom wall 17 terminates in a vertical wall 22 of a dust guard well 23 which is completed by a vertical wall 24. Formed integrally with the depending vertical side walls 16—16 are brass stop columns 25—25 having concave surfaces 26—26 at their lower ends. The brass stop columns 25—25 serve to guide ends 27—27 of a journal brass or bearing 28 that is surmounted by a wedge 29. The side walls 16—16, in the embodiment here shown, are provided with integral waste retaining ribs 30—30 for preventing waste packing 31 containing a lubricant from being carried around the axle journal 11 and between it and the bearing surface of the journal brass or bearing 28.

It will be understood that the construction thus far described with reference to FIGS. 1, 2 and 3 is conventional and that it may be varied in certain respects some of which will be apparent hereinafter.

It is desirable to limit the relative transverse movement of the axle journal 11 with respect to the railway car journal box 14. Such relative movement is likely to be caused during the starting or stopping of the car. It may be caused also as a result of shocks incident to shifting of the car and application of the brakes. In some instances the shift may be sufficient to move the axle journal 11 out of proper operative position with respect to the journal brass or bearing 28.

With a view to limiting such relative movement of the axle journal 11 journal guides 34—34 are provided. They are formed of suitable wear resisting material such as brass. It will be understood that they can be formed of composite material as may be desired. The journal guides 34—34 are interposed between the side walls 16—16 and the respective diametrically opposite sides of the axle journal 11. Each of the journal guides 34—34 includes a body portion 35 having a front face 36 that may be flat or curved and which is juxtaposed to the axle journal 11 as shown. The body portion 35 has a rear face 37 which is curved in part to fit the concave surface 26 at the lower end of the respective brass stop column 25 and in part to rest on the upper surface of the respective waste retaining rib 30. When so positioned, the up and down movement of the journal guide 34 is limited by the concave surface 26 of the brass stop column 25 and the upper surface of the waste retaining rib 30. It remains to describe how the journal guides 34—34 are held in the positions shown in FIG. 1 against movement in the respective vertical planes and also how they are biased against the respective side walls 16—16.

It will be observed that each body portion 35 has a circumferentially grooved intermediate portion 38 that is shaped in order to receive at least one turn 39 of a one

piece spring wire frame that is indicated, generally, at 49 and has a circular cross section. The one piece spring wire frame 40, as above pointed out, serves to hold the journal guides 34—34 against movement in a vertical plane through each of them but also it serves to bias the journal guides 34—34 against the side walls 16—16. In this particular embodiment of the invention the journal guides 34—34 are also held against up and down movement by the concave surfaces 26—26 of the brass stop columns 25—25 and by the upper surfaces of the waste retaining ribs 30—30. However, as will appear hereinafter, either or both of these restraining means may be omitted.

As shown more clearly in FIG. 2 of the drawings the spring wire frame 40 is offset at 41 downwardly past the waste retaining ribs 30—30 to join with a central portion 42 which is intermediate the journal guides 34—34. This central portion 42 bears against the concave inner surface 19 of the end wall 20. The end portions 43—43 of the one piece spring wire frame 40 overlie the side walls 16—16 and their ends 40 (only one being shown) extend through apertures 45 (only one being shown) in the side walls 16—16 adjacent the lid opening 21.

As shown in FIG. 3 each end 44 extends loosely through the aperture 45. If desired, it may be tack welded to the outer side of the respective side walls 16 as shown in FIG. 10.

FIG. 4 shows a modification of the construction illustrated in FIG. 3. Here it will be observed that the end 44 is threaded at 46 to receive a nut 47 which may be tightened to hold the end 44 securely in position.

In order to apply the one piece spring wire frame 40 assembled with the journal guides 34—34, the railway car journal box 14 is jacked upwardly sufficiently far to permit removal of the journal brass or bearing 28 and the wedge 29. Then the one piece spring wire frame 40 with the journal guides 34—34 assembled thereon is inserted through the lid opening 21 sufficiently far to align the journal guides 34—34 with the lower ends of the brass stop columns 25—25 and in positions where they rest on the upper surfaces of the waste retaining ribs 30—30. When properly located, the central portion 42 which interconnects the journal guides 34—34 bears against the concave inner surface 19 of the end wall 20 slightly below the level of the lower edge of the lid opening 21. The ends 44 of the end portions 43—43 are inserted in the apertures 45 in the side walls 16—16. The ends 44 then can be welded in position, if desired, or, if they are threaded as indicated at 46, the lock nuts 47 can be applied. Thereafter the journal brass or bearing 28 and the wedge 29 are replaced and the railway car journal box 14 is lowered to operative position. The journal guides 34—34 are removed by reversing the foregoing steps.

In FIGS. 5, 6 and 7 the railway car journal box 14, previously described, is employed except that the waste retaining ribs 30—30 are not used. This also is a conventional construction which is generally similar in other respects to that previously described.

With a view to centering the axle journal 11 for the reasons outlined hereinbefore, journal guides 50—50 are provided and are positioned between the side walls 16—16 of the railway car journal box 14 and the diametrically opposite sides of the axle journal 11. It will be observed in FIGS. 6 and 7 that the journal guides 50—50 are offset from the brass stop columns 25—25 toward the lid opening 21. Each journal guide 50 includes a body portion 51 having a front face 52 adjacent the axle journal 11. It may be flat or curved as desired. The body portion 51 has a rear face 53 which is generally flat for bearing against the flat inner surface of the side walls 16 adjacent thereto. Between the front and rear faces 52 and 53 the body portion 51 has a circumferentially grooved intermediate portion 54 of such size and shape as to receive two turns 55 of a one piece spring wire frame, shown generally at 56, and having a circular cross sec-

tion. Like the wire frame 40 previously described, the one piece spring wire frame 56 is effective to hold the journal guides 50—50 against movement in their respective vertical planes and also acts to bias them outwardly and against the respective side walls 16—16.

The central portion 57 of the one piece spring wire frame 56 interconnecting the journal guides 50—50 is curved to conform to the concave inner surface 19 of the end wall 20 and it bears against it. The one piece spring wire frame 56 is offset at 58 adjacent each of the journal guides 50—50 and underlies the concave surface 26 of the respective stop column 25 to limit vertical displacement of the frame 56. The end portions 59—59 follow the contours of the side walls 16—16 and the bottom wall 17 to bear against the vertical wall 22 of the dust guard well 23 as shown more clearly in FIG. 6. The ends 60—60, FIG. 5, are juxtaposed adjacent the lowermost portion of the vertical wall 22.

The manner in which the one piece spring wire frame 56 assembled with the journal guides 50—50 is applied is generally the same as that described previously for the application and removal of the one piece spring wire frame 40 with the journal guides 34—34 assembled therewith. Accordingly, this description will not be repeated.

Referring now particularly to the embodiment of the invention shown in FIGS. 8—11, it will be observed that the railway car journal box 14 is the same as previously described except that the waste retaining ribs 30—30 are not illustrated. In this embodiment of the invention use is not made of the vertical wall 22 of the dust guard well 23. In the embodiment of the invention here shown journal guides 64—64 are employed and are positioned in alignment with the brass stop columns 25—25 which are provided with the concave surfaces 26—26 at their lower ends. Each journal guide 64 includes a body portion 65 having a front face 66 juxtaposed to the axle journal 11 and a rear face 67 that is curved to conform to the curvature of the concave surfaces 26—26 against which the upper portion bears. The curvature of the rear face 67 is symmetrical on the upper and lower portions in order to permit using the same journal guide 64 on either side and bearing against the inner side of the respective side wall 16. As before, the journal guides 64—64 are formed of suitable material such as brass or a composite material as may be desired. Each journal guide 64 has a circumferentially grooved intermediate portion 68 around which two turns 69 of a one piece spring wire frame, shown generally at 70, are wrapped. The spring wire frame 70 functions like the spring wire frames 40 and 56 previously described and it acts to hold the journal guides 64—64 against movement in their respective vertical planes and at the same time it biases them outwardly against the side walls 16—16.

It will be observed that the spring wire frame 70 is offset at 71—71 and continues to a central portion 72 which depends centrally from the journal guides 64—64 and interconnects them. The central portion 72 of the spring wire frame 70 is shaped to conform to the curvature of the bottom wall 17 and it bears against it in supporting the journal guides 64—64 in operative position underneath the brass stop columns 25—25 with the upper parts of the curved rear faces 67 juxtaposed to the concave surfaces 26—26 at the lower end of the brass stop columns 25—25.

The spring wire frame 70 includes end portions 73—73 that extend upwardly and outwardly toward the lid opening 21 and overlie and bear against the inner sides of the side walls 16—16. As shown more clearly in FIG. 10 of the drawings, each end 74 of the end portions 73—73 is turned outwardly and extends through an aperture 75 in the side wall 16. It projects sufficiently far to extend beyond the outer surface of the wall 16 and can be tack welded thereto as indicated at 76.

An alternate construction is illustrated in FIG. 11. Here it will be observed that the end 74 is relatively short

and that it projects into an aperture 77 in the form of a recess which extends only part way through the side wall 16.

The one piece spring wire frame 70 assembled with the journal guides 64—64 is applied to the railway car journal box 14 in the manner previously described for the spring wire frame 40 and its journal guides 34—34. The assembly is removed by reversing the application steps. Where the ends 74 are welded as indicated at 76, the weld is cut away in order to release the end portions 73—73 of the spring wire frame 70.

FIGS. 12, 13 and 14 show still another embodiment of the invention. The railway car journal box 14 is of the same construction as previously described except that the waste retaining ribs 30—30 are not used. Also, use is not made in this embodiment of the vertical wall 22 of the dust guard well. The construction here shown includes journal guides 80—80 that are generally similar to the journal guides previously described. They are positioned between diametrically opposite sides of the axle journal 11 and the respective side walls 16—16. Each journal guide 80 includes a body portion 81 having a front face 82 spaced a slight distance from the respective side of the axle journal 11. On the opposite side there is a rear face 83 which is curved to interfit with the concave surface 26 at the lower end of the respective brass stop column 25. The construction is such that the journal guides 80—80 can be used interchangeably for either side.

Each journal guide 80 has a circumferentially grooved intermediate portion 84 around which two turns 85 of a one piece spring wire frame 86 are wrapped. The spring wire frame 86 is preferably circular in cross section and is arranged, like the spring wire frames 40, 56 and 70, to hold the journal guides 80—80 against movement in their respective vertical planes and also to bias them outwardly toward the respective vertical side walls 16—16.

The spring wire frame 86 includes a central portion 87 which extends between the journal guides 80—80, depends therefrom forwardly of the centers thereof and follows the contour of the concave inner surface 18 of the bottom wall 17. The spring wire frame 86 also includes upwardly projecting looped portions 88—88 which extend upwardly along the outer sides of the respective brass stop columns 25—25 and then downwardly and outwardly as portions 89—89 which merge with horizontal portions 90—90 that extend forwardly toward the lower edges of the lid opening 21 with end portions 91—91 at right angles thereto and bearing against the concave inner surface 19 of the end wall 20 just below the lower edge of the lid opening 21. The looped portions 88—88 position the spring wire frame 86 between the inner surface 19 of the end wall 20 and the stop columns 25—25 and hold it in place in the journal box 14. From FIG. 12 it will be observed that the ends 92 of the end portions 91 are juxtaposed near the vertical center line of the railway car journal box 14. The end portions 91 underlie a locking shoulder 93 that may be formed integral with or welded to the end wall 20 along the upper portion of its inner surface 19.

It will be understood that any of the journal guides shown and described herein are held in position against the side walls 16—16 of the railway car journal box 14 so that they do not rattle and are not free to move in any direction. They are interposed between the diametrically opposite sides of the axle journal 11 and the inner sides of the depending vertical side walls 16—16 in order to take the thrust applied by the axle journal 11 when the operation of the railway car is such as to shift the axle journal 11 out of the center position. Because of the relatively small clearance between the journal guides and the axle journal 11, only a slight relative movement is permitted and the axle journal 11 always remains in operative position with respect to its journal brass or bearing 28. While the several journal guides have been

shown as bearing directly against the inner sides of the vertical side walls 16—16, it will be understood that shims may be provided therebetween as may be desired. Also, the journal guides can be formed of composite material having the front face formed of a layer of bearing material, such as brass, and the remainder formed of a less costly material, such as steel. Also, it is contemplated that the journal guides can be formed of other materials and of other composite materials as may be desired.

What is claimed as new is:

1. In combination; a railway car journal box having spaced vertical side walls and an axle journal spaced from said side walls, said side walls being interconnected by a bottom wall; a journal guide interposed between each side wall and the diametrically opposite sides of said axle journal; each journal guide having a body portion with a front face juxtaposed to said axle journal, and a rear face bearing against the respective side wall; and a one piece spring wire frame wrapped around each journal guide intermediate its front and rear faces and restraining the same against movement in a vertical plane and biasing each journal guide against the respective side wall of said journal box.
2. In combination; a railway car journal box having spaced vertical side walls and an axle journal spaced from said side walls, said side walls being interconnected by a bottom wall; a journal guide interposed between each side wall and the diametrically opposite sides of said axle journal; each journal guide having a body portion with a front face juxtaposed to said axle journal, a circumferentially grooved intermediate portion, and a rear face bearing against the respective side wall; and a one piece spring wire frame wrapped around each grooved intermediate portion for restraining each journal guide against movement in a vertical plane and biasing it against the respective side wall of said journal box.
3. In combination; a railway car journal box having spaced vertical side walls and an axle journal spaced from said side walls, said side walls being interconnected by a bottom wall; a journal guide interposed between each side wall and the diametrically opposite sides of said axle journal; each journal guide having a body portion with a front face juxtaposed to said axle journal, a circumferentially grooved intermediate portion, and a rear face bearing against the respective side wall; and a one piece spring wire frame wrapped around each grooved intermediate portion for restraining each journal guide against movement in a vertical plane and biasing it against the respective side wall of said journal box.
4. In combination; a railway car journal box having spaced vertical side walls and an axle journal spaced from said side walls, said side walls being interconnected by a bottom wall terminating at the outer end in an outer wall having a concave inner surface below a lid opening, horizontally extending waste retaining ribs on the inner sides of said vertical side walls, and vertically extending brass stop columns on the inner sides of said vertical side walls; a journal guide interposed between each side wall and the diametrically opposite sides of said axle journal and resting upon the upper side of the respective waste retaining rib; each journal guide having a body portion with a front face juxtaposed to said axle journal, a circumferentially grooved intermediate portion, and a rear face bearing against the respective side wall; and a one piece spring wire frame wrapped around each grooved intermediate portion for restraining each journal guide against movement in a vertical plane and biasing it against the respective side wall of said journal box.
5. In combination; a railway car journal box having

spaced vertical side walls and an axle journal spaced from said side walls, said side walls being interconnected by a bottom wall terminating at the outer end in an outer wall having a concave inner surface below a lid opening, horizontally extending waste retaining ribs on the inner sides of said vertical side walls, and vertically extending brass stop columns on the inner sides of said vertical side walls; a journal guide interposed between each side wall and the diametrically opposite sides of said axle journal and limited in its up and down movement by the lower end of the respective brass stop column and the upper sides of the respective waste retaining rib; each journal guide having a body portion with a front face juxtaposed to said axle journal, a circumferentially grooved intermediate portion, and a rear face bearing against the respective side wall; and a one piece spring wire frame wrapped around each grooved intermediate portion for restraining each journal guide against movement in a vertical plane and biasing it against the respective side wall of said journal box.

6. In combination; a railway car journal box having spaced vertical side walls and an axle journal spaced from said side walls, said side walls being interconnected by a bottom wall terminating at the outer end in an outer wall having a concave inner surface below a lid opening, horizontally extending waste retaining ribs on the inner sides of said vertical side walls, and vertically extending brass stop columns on the inner sides of said vertical side walls; a journal guide interposed between each side wall and the diametrically opposite sides of said axle journal and resting upon the upper side of the respective waste retaining rib; each journal guide having a body portion with a front face juxtaposed to said axle journal, a circumferentially grooved intermediate portion, and a rear face bearing against the respective side wall; and a one piece spring wire frame wrapped around each grooved intermediate portion for restraining each journal guide against movement in a vertical plane and biasing it against the respective side wall of said journal box, the end portions of said one piece spring wire frame overlying the respective side walls of said journal box, the portion of said one piece spring wire frame between the journal guides overlying said concave inner surface of said outer wall of said journal box.

7. In combination; a railway car journal box having spaced vertical side walls and an axle journal spaced from said side walls, said side walls being interconnected by a bottom wall terminating at the outer end in an outer wall having a concave inner surface below a lid opening, horizontally extending waste retaining ribs on the inner sides of said vertical side walls, and vertically extending brass stop columns on the inner sides of said vertical side walls; a journal guide interposed between each side wall and the diametrically opposite sides of said axle journal and resting upon the upper side of the respective waste retaining rib; each journal guide having a body portion with a front face juxtaposed to said axle journal, a circumferentially grooved intermediate portion, and a rear face bearing against the respective side wall; and a one piece spring wire frame wrapped around each grooved intermediate portion for restraining each journal guide against movement in a vertical plane and biasing it against the respective side wall of said journal box, the end portions of said one piece spring wire frame extending toward said lid opening and overlying the respective side walls of said journal box with the ends turned outwardly and interfitting in apertures in said side walls adjacent said lid opening, the portion of said one piece spring wire frame between the journal guides overlying said concave inner surface of said outer wall of said journal box.

8. In combination; a railway car journal box having spaced vertical side walls and an axle journal spaced from said side walls, said side walls being interconnected by a bottom wall having a concave inner surface terminating at the outer end in an outer wall having a concave inner

surface below a lid opening and terminating at its inner end in a vertical wall of a dust guard well; a journal guide interposed between each side wall and the diametrically opposite sides of said axle journal; each journal guide having a body portion with a front face juxtaposed to said axle journal, a circumferentially grooved intermediate portion, and a rear face bearing against the respective side wall; and a one piece spring wire frame wrapped around each grooved intermediate portion and reacting between said concave inner surface of said outer wall and said vertical wall of said dust guard well for restraining each journal guide against movement in a vertical plane and biasing it against the respective side wall of said journal box.

9. In combination; a railway car journal box having spaced vertical side walls and an axle journal spaced from said side walls, said side walls being interconnected by a bottom wall having a concave inner surface terminating at the outer end in an outer wall having a concave inner surface below a lid opening and terminating at its inner end in a vertical wall of a dust guard well; a journal guide interposed between each side wall and the diametrically opposite sides of said axle journal; each journal guide having a body portion with a front face juxtaposed to said axle journal, a circumferentially grooved intermediate portion, and a rear face bearing against the respective side wall; and a one piece spring wire frame wrapped around each grooved intermediate portion and reacting between said concave inner surface of said outer wall and said vertical wall of said dust guard well for restraining each journal guide against movement in a vertical plane and biasing it against the respective side wall of said journal box, the ends of said one piece spring wire frame being juxtaposed and the end portions thereof overlying said concave inner surface of said bottom wall and bearing against said vertical wall of said dust guard well, the portion of said one piece spring wire frame between the journal guides overlying said concave inner surface of said outer wall of said journal box.

10. In combination; a railway car journal box having spaced vertical side walls and an axle journal spaced from said side walls, said side walls being interconnected by a bottom wall having a concave inner surface terminating at the outer end in an outer wall below a lid opening, and vertically extending brass stop columns on the inner sides of said vertical side walls; a journal guide interposed between each side wall and the diametrically opposite sides of said axle journal; each journal guide having a body portion with a front face juxtaposed to said axle journal, a circumferentially grooved intermediate portion, and a rear face bearing against the respective side wall; and a one piece spring wire frame wrapped around each grooved intermediate portion and reacting between said side walls and said concave inner surface of said bottom wall for restraining each journal guide against movement in a vertical plane and biasing it against the respective side wall of said journal box.

11. In combination; a railway car journal box having spaced vertical side walls and an axle journal spaced from said side walls, said side walls being interconnected by a bottom wall having a concave inner surface terminating at the outer end in an outer wall below a lid opening, and vertically extending brass stop columns on the inner sides of said vertical side walls; a journal guide interposed between each side wall and the diametrically opposite sides of said axle journal and limited in its up movement by the lower end of the respective brass stop column; each journal guide having a body portion with a front face juxtaposed to said axle journal, a circumferentially grooved intermediate portion, and a rear face bearing against the respective side wall; and a one piece spring wire frame wrapped around each grooved intermediate portion and reacting between said side walls and said concave inner surface of said bottom wall for restraining each journal

guide against movement in a vertical plane and biasing it against the respective side wall of said journal box.

12. In combination; a railway car journal box having spaced vertical side walls and an axle journal spaced from said side walls, said side walls being interconnected by a bottom wall having a concave inner surface terminating at the outer end in an outer wall below a lid opening, and vertically extending brass stop columns on the inner sides of said vertical side walls; a journal guide interposed between each side wall and the diametrically opposite sides of said axle journal; each journal guide having a body portion with a front face juxtaposed to said axle journal, a circumferentially grooved intermediate portion, and a rear face bearing against the respective side wall; and a one piece spring wire frame wrapped around each grooved intermediate portion and reacting between said side walls and said concave inner surface of said bottom wall for restraining each journal guide against movement in a vertical plane and biasing it against the respective side wall of said journal box, the end portions of said one piece spring wire frame overlying the respective side walls of said journal box, the portion of said one piece spring wire frame between the journal guides depending centrally from the journal guides and overlying said concave inner surface of said bottom wall of said journal box.

13. In combination; a railway car journal box having spaced vertical side walls and an axle journal spaced from said side walls, said side walls being interconnected by a bottom wall having a concave inner surface terminating at the outer end in an outer wall below a lid opening, and vertically extending brass stop columns on the inner sides of said vertical side walls; a journal guide interposed between each side wall and the diametrically opposite sides of said axle journal; each journal guide having a body portion with a front face juxtaposed to said axle journal, a circumferentially grooved intermediate portion, and a rear face bearing against the respective side wall; and a one piece spring wire frame wrapped around each grooved intermediate portion and reacting between said side walls and said concave inner surface of said bottom wall for restraining each journal guide against movement in a vertical plane and biasing it against the respective side wall of said journal box, the end portions of said one piece spring wire frame extending toward said lid opening and overlying the respective side walls of said journal box with the ends turned outwardly and interfitting in apertures in said side walls adjacent said lid opening, the portion of said one piece spring wire frame between the journal guides depending centrally from the journal guides and overlying said concave inner surface of said bottom wall of said journal box.

14. In combination; a railway car journal box having spaced vertical side walls and an axle journal spaced from said side walls, said side walls being interconnected by a bottom wall having a concave inner surface terminating at the outer end in an outer wall having a concave inner surface below a lid opening, and vertically extending brass stop columns on the inner sides of said vertical side walls; a journal guide interposed between each side wall and the diametrically opposite sides of said axle journal; each journal guide having a body portion with a front face juxtaposed to said axle journal, a circumferentially grooved intermediate portion, and a rear face bearing against the respective side wall; and a one piece spring wire frame wrapped around each grooved intermediate portion and reacting between said concave inner surface of said outer wall and said concave inner surface of said bottom wall for restraining each journal guide against movement in a vertical plane and biasing it against the respective side wall of said journal box.

15. In combination; a railway car journal box having spaced vertical side walls and an axle journal spaced from said side walls, said side walls being interconnected by a bottom wall having a concave inner surface terminating at the outer end in an outer wall having a concave inner

surface below a lid opening, and vertically extending brass stop columns on the inner sides of said vertical side walls; a journal guide interposed between each side wall and the diametrically opposite sides of said axle journal and limited in its up movement by the lower end of the respective brass stop column; each journal guide having a body portion with a front face juxtaposed to said axle journal, a circumferentially grooved intermediate portion, and a rear face bearing against the respective side wall; and a one piece spring wire frame wrapped around each grooved intermediate portion and reacting between said concave inner surface of said outer wall and said concave inner surface of said bottom wall for restraining each journal guide against movement in a vertical plane and biasing it against the respective side wall of said journal box.

16. In combination; a railway car journal box having spaced vertical side walls and an axle journal spaced from said side walls, said side walls being interconnected by a bottom wall having a concave inner surface terminating at the outer end in an outer wall having a concave inner surface below a lid opening, and vertically extending brass stop columns on the inner sides of said vertical side walls; a journal guide interposed between each side wall and the diametrically opposite sides of said axle journal; each journal guide having a body portion with a front face juxtaposed to said axle journal, a circumferentially grooved intermediate portion, and a rear face bearing against the respective side wall; and a one piece spring wire frame wrapped around each grooved intermediate portion and reacting between said concave inner surface of said outer wall and said concave inner surface of said bottom wall for restraining each journal guide against movement in a vertical plane and biasing it against the respective side wall of said journal box, the ends of said one piece spring wire frame being juxtaposed and the end portions thereof overlying said concave inner surface on said outer wall, the portion of said one piece spring wire frame between the journal guides overlying said concave inner surface of said bottom wall of said journal box.

17. In combination; a railway car journal box having spaced vertical side walls and an axle journal spaced from said side walls, said side walls being interconnected by a bottom wall having a concave inner surface terminating at the outer end in an outer wall having a concave inner surface below a lid opening, and vertically extending brass stop columns on the inner sides of said vertical side walls; a journal guide interposed between each side wall and the diametrically opposite sides of said axle journal and limited in its up movement by the lower end of the respective brass stop column; each journal guide having a body portion with a front face juxtaposed to said axle journal, a circumferentially grooved intermediate portion, and a rear face bearing against the respective side wall; and a one piece spring wire frame wrapped around each grooved intermediate portion and reacting between said concave inner surface of said outer wall and said concave inner surface of said bottom wall for restraining each journal guide against movement in a vertical plane and biasing it against the respective side wall of said journal box, the portion of said one piece spring wire frame extending from the portion thereof wrapped as aforesaid projecting upwardly and forming a reverse turn and bearing against the side of the respective brass stop column facing said lid opening.

18. In combination; a railway car journal box having spaced vertical side walls and an axle journal spaced from said side walls, upper portions of said side walls having vertically extending and inwardly projecting brass stop columns, said side walls being interconnected by a bottom wall; a journal guide interposed between each side wall and the diametrically opposite sides of said axle journal; each journal guide having a body portion with a front face juxtaposed to said axle journal, and a rear

face bearing against the respective side wall; and a one piece spring wire frame secured to each journal guide intermediate its front and rear faces and extending under and reacting against overhanging surfaces of said brass stop columns on said side walls, said one piece spring wire frame restraining said journal guides against vertical and horizontal movement and biasing each journal guide against the respective side walls of said journal box and restraining the same against movement in a vertical plane.

19. In combination; a railway car journal box having spaced vertical side walls and an axle journal spaced from said side walls, upper portions of said side walls having vertically extending and inwardly projecting brass stop columns, said side walls being interconnected by a bottom wall having a concave inner surface terminating at the outer end in an outer wall having a concave inner surface below a lid opening and terminating at its inner end in a vertical wall of a dust guard well; a journal guide interposed between each side wall and the diametrically opposite sides of said axle journal; each journal guide having a body portion with a front face juxtaposed to said axle journal, a circumferentially grooved intermediate portion, and a rear face bearing against the respective side wall; and a one piece spring wire frame wrapped around each grooved intermediate portion, extending under and reacting against overhanging surfaces of said brass stop columns on said side walls, and reacting between said concave inner surface of said outer wall and said vertical wall of said dust guard well for restraining each journal guide against movement in a vertical plane and biasing it against the respective side wall of said journal box, the ends of said one piece spring wire frame being juxtaposed and the end portions thereof overlying said concave inner surface of said bottom wall and bearing against said vertical wall of said dust guard well, the portion of said one piece spring wire frame between the journal guides overlying said concave inner surface of said outer wall of said journal box for restraining each journal guide against horizontal movement.

20. In combination; a railway car journal box having spaced vertical side walls and an axle journal spaced from said side walls, said side walls being interconnected by a bottom wall having a concave inner surface terminating at the outer end in an outer wall having a concave inner surface below a lid opening, a locking shoulder on the inner side of said outer wall adjacent said lid opening, and vertically extending brass stop columns on the inner sides of said vertical side walls; a journal guide interposed between each side wall and the diametrically opposite sides of said axle journal and limited in its up movement by the lower end of the respective brass stop column; each journal guide having a body portion with a front face juxtaposed to said axle journal, a circumferentially grooved intermediate portion, and a rear face bearing against the respective side wall; and a one piece spring wire frame wrapped around each grooved intermediate portion and reacting between said concave inner surface of said outer wall and underneath said locking shoulder thereon and said concave inner surface of said bottom wall for restraining each journal guide against horizontal and vertical movement and biasing it against the respective side wall of said journal box.

21. In combination; a railway car journal box having spaced vertical side walls and an axle journal spaced from said side walls, said side walls being interconnected by a bottom wall having a concave inner surface termi-

nating at the outer end in an outer wall having a concave inner surface below a lid opening, and vertically extending brass stop columns on the inner sides of said vertical side walls; a journal guide interposed between each side wall and the diametrically opposite sides of said axle journal; each journal guide having a body portion with a front face juxtaposed to said axle journal, a circumferentially grooved intermediate portion, and a rear face bearing against the respective side wall; and a one piece spring wire frame wrapped around each grooved intermediate portion and reacting between said concave inner surface of said outer wall and said concave inner surface of said bottom wall for restraining each journal guide against movement in a vertical plane and biasing it against the respective side wall of said journal box, the ends of said one piece spring wire frame being juxtaposed and the end portions thereof overlying said concave inner surface on said outer wall, the portion of said one piece spring wire frame between the journal guides overlying said concave inner surface of said bottom wall of said journal box at a location toward the front of said journal box to provide positive rotation effect of said journal guides due to their mass and cause positive contact between them and their juxtaposed portions of said journal box.

22. In combination; a railway car journal box having spaced vertical side walls and an axle journal spaced from said side walls, said side walls being interconnected by a bottom wall having a concave inner surface terminating at the outer end in an outer wall having a concave inner surface below a lid opening, and vertically extending brass stop columns on the inner sides of said vertical side walls; a journal guide interposed between each side wall and the diametrically opposite sides of said axle journal and limited in its up movement by the lower end of the respective brass stop column; each journal guide having a body portion with a front face juxtaposed to said axle journal, a circumferentially grooved intermediate portion, and a rear face bearing against the respective side wall; and a one piece spring wire frame wrapped around each grooved intermediate portion and reacting between said concave inner surface of said outer wall and said concave inner surface of said bottom wall for restraining each journal guide against movement in a vertical plane and biasing it against the respective side wall of said journal box, the portion of said one piece spring wire frame extending from the portion thereof wrapped as aforesaid projecting upwardly and forming a reverse turn and bearing against the side of the respective brass stop column facing said lid opening thereby restricting movement of said journal guides toward the rear of said journal box while the portion of said one piece spring wire engaging said inner surface of said outer wall restricts movement of said journal guides in the opposite direction.
